UNITED STATES PATENT OFFICE.

ISAAC GORDON, OF KENOSHA, WISCONSIN.

SCISSORS-HOLDER.

SPECIFICATION forming part of Letters Patent No. 368,943, dated August 30, 1887.

Application filed May 18, 1887. Serial No. 238,684. (No model.)

To all whom it may concern:

Be it known that I, ISAAC GORDON, a citizen of the United States, residing at Kenosha, in the county of Kenosha and State of Wisconsin, 5 have invented a new and useful Improvement in Scissors-Holders, of which the following is a specification.

My invention relates to a peculiar and simple device to hold scissors which is adapted to be secured to the dress of the user by any suitable means, as a pin, whereby when the scissors are not in use they may be secured by a single motion in the said holder, and will remain firmly in place until needed, when they 15 may be very easily disengaged.

In the drawings hereto annexed, Figure 1 is a perspective view showing the scissors in position in the holder. Fig. 2 is a rear view of the same. Fig. 3 is a transverse section of 25 the same. Fig. 4 is a front view showing a different manner of securing the spring-tongues in place.

Referring to the drawings by letter, A designates the rear plate, having the vertical parallel apertures or slots B B formed therein, the tongues C C, which are cut out of the said slots, being allowed to remain in place at the lower ends. The said tongues are bent at their middle points to form the angular projections c c, 30 beveled on the upper and lower sides, and, as the upper ends of the tongues are free, it will be seen that if the said projections are pressed rearwardly the tongues will pass through the slots B.

D designates a spring-leaf secured to or formed integral with the upper edge of the plate A and adapted to press rearwardly against the projections c c of the tongues. The said leaf may be either solid or formed in any preferred ornamental design, to render the holder attractive in appearance, and a pin, E, is secured to the rear side of the plate A to enable the device to be secured to any desired part of the dress of the user.

The entire device is preferably made of 45 spring-steel, and to secure a pair of scissors therein pass the eyes of the handles up under the leaf D, and as the said eyes ascend they will slide up on the beveled lower sides of the 50 projections c, cause the tongues C to be de-

pressed, and when far enough up the said tongues will resume their normal positions and the projections will pass into the eyes of the scissors and hold the same in place.

When the scissors are needed, it is only necessary to draw down upon them and the tongues are again depressed, allowing the scissors to be withdrawn.

In addition to the outward pressure of the spring-tongues C, the leaf D presses inwardly 60 upon the scissors, and it will be seen that in some cases the tongues may be altogether omitted, and the spring-leaf will hold the scissors merely by the said pressure; also, the projections c, instead of being movable, may be 65 made stationary on the plate A.

It will be seen that the device is very simple and the scissors are attached or detached by a simple upward or downward pressure.

As an additional security, to prevent the 70 scissors from slipping out of the holder after having been placed therein, I form the leaf D with the grooves d d on the lower side, to receive the beveled projections on the spring-tongues. It is obvious that by this arrangement the leaf D may be disposed closer to the 75 plate A than if the grooves were not formed, and it is slightly more difficult to disengage the scissors.

It will be understood that I do not limit myself to constructing the tongues integrally with the plate, as it is obvious that if the said plate and leaf were made of cast or malleable metal and provided below the grooves therein with small apertures w w, as seen in Fig. 4, and 80 spring-tongues secured in the said apertures and provided with an enlargement or shoulder on the lower end to prevent the same from being disengaged from the said apertures, that the operation of the device would be the same 85 90 as in the construction shown in Figs. 1 to 3.

Having now described the construction, operation, and advantages of my invention, what I claim, and desire to secure by Letters Patent of the United States, is—

1. As an improved article of manufacture, a scissors-holder consisting of front and rear plates, A and D, bent into shape from a single piece of metal, the said plate A having depressed spring-tongues C, the points c of which 95 100

are adapted to engage with the grooves *d*, formed in the rear side of the plate *D*, substantially as described.

2. In a scissors-holder, the combination, with 5 the plates *A* and *D*, bent into shape, as set forth, of the two depressed spring-tongues *C*, adapted to engage with the rear side of the plate *D*, substantially as described.

3. In a scissors-holder, the combination of 10 the two plates *A* and *D*, bent into the form set forth from a single piece of metal, the two de-

pressed spring-arms *C*, having a pin-clasp, *E*, secured to the plate *A* in the rear of the said springs *C*, substantially as set forth.

In testimony that I claim the foregoing as 15 my own I have hereto affixed my signature in presence of two witnesses.

ISAAC GORDON.
